UNITED STATES PATENT OFFICE

ARTHUR N. EMMONS, OF SYRACUSE, NEW YORK, ASSIGNOR TO THE PORTER-CABLE
MACHINE COMPANY, OF SYRACUSE, NEW YORK, A CORPORATION OF NEW YORK

DESIGN FOR AN ABRADING MACHINE

Application filed April 19, 1933. Serial No. 47,835. Term of patent 7 years.

To all whom it may concern:

Be it known that I, ARTHUR N. EMMONS, a citizen of the United States, residing at Syracuse, in the county of Onondaga and State of New York, and having my postoffice address at 107 East Roswell Road, Syracuse, New York, have invented a new, original, and ornamental Design for an Abrading Machine, of which the following is a specification, reference being had to the accompanying drawings forming part thereof.

Figure 1 is an approximately three-quarters perspective view taken from the front.

Figure 2 is an approximately three-quarters perspective view taken from the rear.

Figure 3 is a rear elevation.

Figure 4 is a front elevation.

I claim:

The ornamental design for an abrading machine substantially as shown.

In testimony whereof, I have hereunto signed my name, at Syracuse, in the county of Onondaga and State of New York, this 17th day of April, 1933.

ARTHUR N. EMMONS.
